WALL CONSTRUCTION

Louis C. Piazza, Western Springs, Ill., assignor
to Soundex Corporation, Chicago, Ill., a corpora-
tion of Illinois

Application December 4, 1930, Serial No. 499,922

8 Claims. (Cl. 72—19)

This invention relates broadly to the application of exterior covering materials to a room construction, and is more particularly concerned with a novel and improved wall and ceiling construction, that is to say, with a novel method and with novel means for attaching covering material to a wall or to a ceiling.

I employ as covering material a sound correcting substance, consisting generally of wood fibres pressed in blocks or slabs and held together by suitable adhesive binding substance. A block of such material may be produced in any convenient size and then cut into slabs or plates of suitable smaller size for attachment to the ceiling or wall in the novel manner which is disclosed in the present invention.

It will be understood, of course, that the novel construction, which I have disclosed in the instant case in connection with a ceiling, is not limited to the use of any particular sound correcting or sound dissipating substance or material, or, in fact, to any particular substance or material. I have mentioned wood fibres pressed in blocks or slabs of suitable size merely for the sake of convenient description. Any other suitable material or substance may be employed and attached to the ceiling of a room in accordance with the teachings of my invention, either for purely decorative purposes or for correcting acoustics or both. It will likewise be understood that I do not intend to limit the applicability of the invention strictly and literally to the construction of ceilings. The basic principles may also be applied in the construction of walls if desired, or to structures resembling walls.

The invention discloses, therefore, the broad principles of a novel and improved method for attaching exteriorly exposed covering material to walls or ceilings in an efficient and economic manner.

There are several methods known and practiced for attaching sound correcting material to walls and to ceilings in order to correct the acoustics of rooms.

For example, one method proposes to attach the material by means of plaster, thus merging the material with the underlying rigid building structure. Another method provides a felt padding between the sound correcting material and the wall or ceiling structure, securing the material by means of nails or screws, or otherwise by means of some convenient adhesive together with nails or screws.

Several objections may be raised as to the sound

deadening or sound correcting quality of such a structure made in the manner outlined above. The close attachment of the sound correcting material to a wall or ceiling, as by means of plaster, diminishes its effect due to the rigid character of the underlying building structure. The mounting consumes considerable time since it is not a purely mechanical process, but depends to a large extent on the quality of the plaster or other binding material employed. Finishing work is necessary in order to remove undesirable traces of plaster or binding material from crevices of adjacent slabs of the covering material. The structure is rigid and does not lend itself readily to changes or modifications which might be desired.

The other method mentioned previously, which employs felt padding between the ceiling or wall structure and the exteriorly exposed sound correcting material, furnishes a better acoustic effect due to the intervening layer of felt or the like, but occasions considerable expenses and exhibits a structural rigidity similar to the first mentioned method, making changes difficult and costly.

It is the main and principal object of my invention to produce a structure of this character which is simple in design, inexpensive in installation, of utmost flexibility, and which combines all the advantages of prior structures while avoiding their faults. If employed for acoustic purposes, the sound correcting qualities of certain embodiments of my invention will be found to be superior due to providing a structure which utilizes the sound dissipating function of the covering slabs to the fullest extent without resorting to the provision of an intermediate layer of felt or the like to separate the covering slabs from the rigid structure of the building.

I provide in one embodiment of my invention slabs or plates of sound correcting material and equip these slabs with simple brackets having tongues which project from opposite sides of the slabs. These tongues are used for attaching the covering slabs to channel shaped carriers which are fastened to the steel beams or girders of the building structure. The attachment of the channel shaped carriers to the girders may be accomplished by means of screws, thereby providing a convenient framework for supporting the exteriorly exposed covering slabs. The tongues of the brackets of each covering slab which project from one side of the same are fastened to a corresponding channel-shaped carrier, while the tongues projecting from the other side of

the covering slab are slipped under the adjacent slab and supported thereby. In other words, there is a framework of channel-shaped carriers attached to the girders in parallel relation to 5 each other, and the covering slabs (which may or may not be made of sound correcting material) are fastened to these carriers in rows extending transversally to the framework in such a manner that each slab is attached on one side 10 to a carrier while its other side is supported by the adjacent slab in the corresponding row. The attachment of slabs at the end of each row is slightly different as will presently appear.

This structure represents a novel method of 15 constructing a covering for a wall or ceiling and simplifies the mounting of the exteriorly exposed covering material considerably. It is merely necessary to slip a covering slab into place with the tongues of the brackets projecting from one 20 side of a slab placed under the adjacent slab, and to screw the tongues projecting from the opposite side of the covering slab to the next channel-shaped carrier. One row of slabs is thus mounted across the entire width of a ceiling or 25 a wall, and the next and successive rows are mounted in the same manner, until the work is finished and the ceiling or wall is covered as desired, presenting a clean and neat appearance.

In another embodiment of the invention I provide 30 strips of suitable supporting material disposed in parallel and depending from angular supporting girders on the ceiling or projecting from a wall in case of a wall structure. The slabs of covering material are disposed between these 35 strips and fastened thereto by means of suitable double pointed nails in a manner which will be described in detail later on.

In a further embodiment I attach to the slabs 40 of covering material simple brackets as in the case mentioned previously, but arrange these brackets on an angle, thereby making each slab interchangeable in any position in one plane relative to the supporting framework.

I have also provided for using the invention 45 in one embodiment in conjunction with a moulded structure. Specifically, I have shown an embodiment in which the slabs are provided with prongs extending laterally from bracket members on the slabs. The ceiling or wall may be 50 formed by supporting the slabs, equipped with such prong-brackets, on a platform and by pouring concrete in the rear of the slabs. The prongs will be embedded in this manner in the concrete and hold the slabs in uniform predetermined 55 position and on a predetermined level corresponding to the mould structure.

Various effects can be produced by predetermining the formation of the slabs in accordance with a desired design or pattern. For example, 60 a lattice effect may be produced by arranging covering slabs of desired size accordingly. The slabs may also be mounted in circular formation if desired. These possibilities are obvious and need not be discussed in detail.

It will at once be seen that the basic principles 65 involved in my invention refer fundamentally to the construction of walls or ceilings, that is to say, to the attachment of exteriorly exposed covering material to a structural framework, regardless of 70 the function of the covering material which may be purely decorative or sound correcting. In my invention, the function of the covering material is shown to be sound correcting and decorative at the same time. The broad idea, however, disregards the function of the covering slabs entirely;

any suitable material of purely decorative character may be attached to walls or to ceilings by following the principles of my invention. Likewise, the term—wall—as used in this specification is intended to cover broadly the structure of a wall or a ceiling as well as a structure resembling a wall, such as a partition, for example.

I have briefly enumerated below the various outstanding objects and features of my invention so that the detailed description and the claims may be readily understood and appreciated.

One object of the invention is concerned with the application of exteriorly exposed covering material to a wall or ceiling comprising a supporting framework, and cover plates disposed on said framework in rows transversal to said framework.

Another object relates to the mounting of exteriorly exposed covering plates or slabs to a wall, comprising a plurality of carriers disposed parallel to each other in one plane, cover plates for bridging attachment to said carriers in rows transversely thereto, and bracket means on said slabs for supporting one side of a slab directly on a carrier and for supporting its other side in interlocking engagement with an adjacent plate or slab.

A further object has to do with the provision of a cover plate for exterior attachment to a wall, and bracket means for mounting said plate, said bracket means including members for fastening 105 said bracket to said plate and projecting members for mounting said plate.

Another object refers to the construction of a wall or ceiling and the like, comprising a structural framework having depending members disposed 110 in parallel relation, cover plates for attachment intermediate of said depending members, and means for lateral engagement with said plates for holding said plates in place relative to said depending members and to said framework.

Still another object relates to cover plates for attachment to a wall and the like, and bracket means on each of said plates for interchangeable attachment thereof in any position of said plates in one plane.

A further object is concerned with the construction of a wall and the like, comprising cover plates, each provided with prongs for holding said plates in engagement with a moulded structure.

Still another object has to do with the construction of walls and the like, comprising means for supporting a plurality of cover plates or slabs for attachment to a wall or ceiling, and bracket means on each plate or slab adapted to be embedded in a suitable substance poured in liquid 130 form on said plates or slabs, thereby embedding said bracket means therein.

I have enumerated above only the outstanding objects of my invention. There are other objects which will appear as the description progresses.

Now, in order to enable others to reproduce my invention and to apply the same to practical use, I will describe the invention in detail with reference to the accompanying drawings in which:

Figure 1 represents a somewhat diagrammatic perspective view of my novel construction of a ceiling;

Figure 2 shows part of a slab of sound correcting 145 covering material for attachment to the ceiling;

Figure 3 illustrates the function of the brackets attached to each covering slab, and the relation to the other like brackets of adjacent covering slabs as viewed from above, that is, as viewed 150

from the channel-shaped carriers which support the covering slabs;

Figure 4 is a section of the arrangement shown in Figure 3, taken on line 4-4 of that figure;

5 Figure 5 is a detail, illustrating particularly the screw attachment of the projecting tongues of the brackets;

10 Figure 6 shows the manner of fastening the channel-shaped supporting carriers to the girders of a ceiling structure;

Figure 7 is particularly intended to illustrate the manner of attaching a covering slab at the end of a row of such slabs and in the corner where the ceiling meets the wall of the room;

15 Figure 8 represents one example of a structure for mounting on a slab or slabs of different size;

Figure 9 shows an embodiment in which the cover slabs are attached by means of double pointed nails;

20 Figure 10 represents a nail to be used in conjunction with the embodiment shown in Figure 9;

Figure 11 illustrates a modification, which may be adopted in connection with the embodiment shown in previous figures, of cover slabs having brackets attached thereto at an angle so as to make the cover slabs interchangeable in any position in one plane; and

Figure 12 shows the embodiment of a cover slab provided for attachment by means of moulding.

30 Referring now particularly to Figure 1, it will be seen that I have provided a number of channel-shaped carriers 1, 2, 3, 4, 5, 6, 7 and 8, each of which is attached to the ceiling structure. The channel-shaped carriers may be attached to the ceiling structure for example in a manner as is particularly illustrated in Figure 6. As shown in this figure, attached to the girders such as 9 and 10 may be bars such as the bar 11, the attachment being made by means of bolts and screws 40 as indicated by numerals 12 and 13. Each bar such as 11 serves to support a channel-shaped carrier such as the one indicated in Figure 6 by the reference numeral 14.

Now again referring to Figure 1, it will be seen that the channel-shaped carriers 1 to 8, inclusive, are separated from each other by predetermined distances corresponding to the shape and size of the covering slabs such as indicated by the numeral 15. I have shown two rows 16 and 17 completed across the width of the room with the exception of a space in the right hand corner of the room. The row designated by the reference numeral 18, however, is shown to be completed only up to the channel-shaped carrier designated by numeral 5. Before continuing the description of the attachment of the slabs, the structure of a slab provided with a bracket for fastening the same to the channel-shaped supporting member will be described in detail.

60 Referring now particularly to Figure 2, this figure shows a portion of a covering slab such as the one indicated in Figure 1 by the numeral 15. Attached to the lower side of the slab are two brackets or fastening members. The ends of each of the fastening members are slit longitudinally, thereby providing at each end a member for attaching the bracket to the slab and a tongue which projects laterally from the slab. This is shown in Figure 2. The slab 19 shown in this figure, or rather to say the portion of the slab 19 which is illustrated in this figure, shows that a supporting member or bracket 20 is attached to the lower side of the slab 19. The end of the supporting member 20 is slit, providing a projecting tongue 21 and a tongue 22 for at-

80 tachment to the slab 19. The attachment of the tongue 22 to the slab is by means of a nail such as 23. The projecting tongue 21 is provided with a hole 24 which serves for fastening the slab to a corresponding channel-shaped carrier as shown in Figure 1. It is, of course, understood that the other side of the bracket member 20, shown in Figure 2, is correspondingly shaped, that is to say it provides a projecting tongue on the other side of the slab 19 and also a fastening tongue such as 22 for attaching the other side of the member 20 to the slab 19. There is only part of the slab 19 shown in Figure 2. There are in reality two such brackets as 20 attached to a slab.

85 Now referring to Figure 3, the attachment of the individual covering slabs to the channel-shaped carriers will be more particularly explained. The view shown in Figure 3 is taken from above, that is to say, from that side of the slabs which are in engagement with the channel-shaped carriers. It will be seen that there are three slabs shown in Figure 3 and designated by the reference numerals 25, 26 and 27. The covering slab 25 is provided with two brackets designated by numerals 28 and 29; the central slab is 90 provided with brackets designated by numerals 30 and 31; and the slab 27 is provided with two brackets designated by the numerals 32 and 33. The end of each bracket is slit and attached to the corresponding covering slab as particularly 95 discussed in connection with Figure 2. For example, referring particularly to the bracket designated by the reference numeral 30, which is attached to the slab 26 in Figure 3, it will be seen that the tongues 34 and 35 of the bracket 100 30 project laterally from the slab 26, while the end members adjacent to the tongues 34 and 35 have been utilized for fastening the bracket 30 to the slab 26 by means of the nails such as 37 and 38. The attachment of each of the brackets 105 to the corresponding slab is similar. It will also be seen that the brackets are attached to the corresponding slabs slightly offset from the center. The offset arrangement of the brackets relative to the individual slabs permits convenient 110 assembly of a plurality of slabs in one row, the brackets of one slab being arranged so as not to interfere with the brackets of the adjacent slabs, and also provides for interchangeability of the individual slab. For example, the slab 26, if 115 turned about by 180 degrees, may be used in place of the slabs 25 or 27. This is an important feature as it provides for standardization of the individual slab.

120 The manner in which the attachment of the 130 slabs to the channel-shaped carrier is accomplished will now be described again with reference to Figure 3. It will be seen that the projecting tongues 39 and 40 of the brackets 28 and 29 which are attached to the covering slab 25 are 125 fastened to the channel-shaped carrier 41 by means of the screws 42 and 43. Thus, the side of the slab 25 which is shown in Figure 3 is fastened directly to the channel-shaped carrier 41. The adjacent slab 26 is now pushed in place 130 by slipping the projecting tongues 34 and 42 under the slab 25. No fastening of these tongues 34 and 42 of the slab 26 is necessary, as this side of the slab 26 will be sufficiently supported by the tongues 34 and 42 which are slipped under 140 the slab 25. The other side of the slab 26 is fastened to the channel-shaped carrier 41A by directly attaching the tongues 35 and 44 to the carrier 41A by means of screws 45 and 46. The 145 next slab 27 is put in place by slipping the tongues 150

47 and 48 of the brackets 32 and 33 under the slab 26 while the tongues projecting from the other side of the slab 27 are again fastened to the next channel-shaped carrier of the supporting structure.

5 The above described manner of attachment will be better understood by referring to the cross-section taken on line 4-4 of Figure 3 as shown in Figure 4. It will be seen that the slab 25 is 16 equipped with a bracket member 29, the tongue 39 of the same projecting laterally from the slab 25. This tongue is attached to the channel-shaped carrier 41 by means of the screw 43. The slab 25 is equipped with a companion bracket similar to the one shown at 29, the projecting tongue of which is also attached to the channel-shaped carrier 41 as is particularly shown in Figure 3. The carrier 41 is shown fastened to the supporting structure by means of screws such as 50 and 20 51. It will be understood, of course, that the arrangement shown in Figure 6 may also be used if desired. The covering slab 26 is also equipped with two brackets as is particularly shown in Figure 3. The tongues of the brackets projecting 25 from the left side of the slab 26 as viewed in Figure 4 are slipped under the slab 25 in a manner illustrated in Figure 3, thus holding this side of the slab 26 in place. The tongues projecting from the bracket 26 to the right side of the 30 same are attached to the channel-shaped carrier 41A as is shown in Figure 3. The carrier itself is again mounted by means of screws such as 52 and 53. The slab 27 is put into place by slipping the projecting tongues such as 48 under the slab 35 26 as shown.

It will at once be seen that the manner of attaching the individual slab and thus forming a covering structure has considerable advantage over what is known in the art. The covering slabs 40 are standardized, or they may be cut in shapes and sizes to conform to a definitely desired pattern or design and are mounted in a very simple manner. The mounting of the covering slabs can be accomplished very neatly and rapidly since 45 all that is necessary is to slip a covering slab into place and to attach the free side of the same to a carrying framework, a process which is extremely simple, eliminating all guesswork and expert attention, and at the same time renders 50 neat work and secure mounting of the structure.

In Figure 7 is shown the manner of completing a row of slabs in the corner, for example, in the right hand corner shown in Figure 1. This 55 last slab which is designated in Figure 7 by the reference numeral 56 may either be of the same size as the preceding slabs or may be of an odd size, depending upon the total width or length of the room and the desired ceiling pattern. The 60 channel-shaped carriers 7' and 8' shown in Figure 7 may correspond to the carriers 7 and 8 shown in Figure 1. The attachment of the intermediate covering slabs such as 54 and 55 has been discussed previously so that the further 65 discussion of Figure 7 may be limited to the attachment of the end slab 56. This slab is put in place against a strip of angle iron designated by reference numeral 57. This angle iron may be attached to the wall in some convenient manner. The slab is put into place against the strip 70 57 and its lower side is held in place by a strip such as 58 fastened to the wall in a similar manner as the strip 57. A tie nail such as 59 may be employed for fastening the end slabs such as 56 to the preceding slabs such as 55 in each row.

I have shown a tie nail for convenience sake. It is of course understood that the end slabs such as 56 may be provided each with brackets having projecting tongues corresponding to the projecting tongues such as 47 and 48 in Figure 3 80 for slipping the same under the preceding slabs and thus holding them from displacement.

85 In Figure 5 is shown a detail, namely, the manner of attaching the projecting tongues to the channel-shaped carriers by means of screws. This figure will be readily understood with the foregoing discussion in mind. Numeral 60 in Figure 5 designates the lower part of a channel-shaped carrier; numeral 61 represents a projecting tongue of one of the brackets attached to one of the covering slabs and numeral 62 shows a screw which is drawn through the hole in the projecting tongue 61 and screwed into the channel-shaped member 60. Threaded holes may be provided in the channel-shaped carriers in advance of mounting the slabs. However, it will be more convenient and more practical to put each slab separately into place and after the same is put in place to bore a hole according to the location of the projecting tongue where the 100 attachment for these tongues are needed. This can be done conveniently and rapidly with a small hand drill.

105 In Figure 8 I have shown a modification or rather to say the manner of applying my invention in places or locations where differently sized covering slabs or plates of considerable size are desired or required. For example, it may be desirable to form the ceiling of a small room or of a corridor or a closet by using only one or two 110 covering slabs of suitable size. If this is the case, it will be necessary to provide only one channel-shaped carrier such as the one indicated in Figure 8 by the numeral 63. This channel-shaped carrier 63 may be attached to the 115 structure of the ceiling in the usual manner by screws such as 64 and 65. An angular member 66 is mounted on one side on the wall and a similar angular member 67 is mounted on the other wall for aligning the covering slab 68 similarly as was discussed in connection with the slab 56 shown in Figure 7. Angular members 69 and 70 are mounted on the opposite walls in order to locate the covering slab 68 in position. A bracket such as 71 may be mounted on the 125 covering slab 68 by bending projecting tongues such as 72 and 73 and fastening these tongues by means of nails to the covering slab 68, firmly attaching the bracket member 71 thereto. This bracket member 71 is then fastened to the channel-shaped carrier 63 by means of screws such as 74.

130 Now, referring particularly to Figure 9, I have shown in this figure an embodiment of the invention in which provisions are made for attaching the cover plates by means of double-headed nails instead of attaching the cover plates by means of screws. In this particular modification shown in Figure 9, no brackets need to be provided on the cover plates. The structural framework comprises pairs of supporting members such as shown by reference numerals 75 and 76. The supporting members may be channel-shaped girders of suitable dimensions as shown. A strip 77 is interposed between the carriers 75 and 76. The strip 77 depends from the carriers as shown in the drawings (Figure 9) and serves the purpose of receiving and of holding the cover plates such as indicated by the reference numerals 78 and 79. It will be understood,

of course, that there are several pairs of supporting members such as 75 and 76 disposed in parallel relation, providing the structural framework for the attachment of the cover plates. 5 Each pair of carriers holds a strip such as 77. The cover plates are fastened to the structural framework intermediate of the strips extending in parallel relation relative to each other along the wall or the ceiling. The cover plates are cut 10 to suitable size. No brackets need to be provided on the cover plates. The attachment is made by means of double-pointed nails such as 80 and 81.

The double-pointed nail is shown in Figure 10. 15 It will be seen that the nail is provided with a center flange 82. A suitable hollow tool may be used for driving such a nail into the corresponding cover plate in the position shown in Figure 9. The strip such as 77 may be provided with a 20 series of holes such as indicated by the reference numerals 83 and 84. The attachment of the cover plate is simply achieved by driving the nails such as 80 and 81 through holes in the strip 77, thereby fastening the cover plate 78 on one side 25 thereof. The nails 80 and 81 now extend from the strip 77 as is shown in the drawings (Figure 9). The next cover plate or slab such as 79 is now attached by driving the same in the direction shown by the arrow, toward the assembly 30 on the left side of Figure 9, whereby the extending portions of the nails 80 and 81 will be driven into the cover plate 79 and hold the same on its left side. Its other side will be attached in the same manner as the right side of plate 78. If it 35 is desired, the spaces between adjacent cover plates may be covered by plaster in order to conceal the edges of the strips such as 77.

In Figure 11 I have shown two cover plates 85 and 86. The cover plate 85 is provided with 40 two brackets 87 and 88. These brackets may conform in general to the shape of the brackets discussed previously in connection with Figures 1 to 8 inclusive. It will be recalled that the brackets shown in connection with the previously discussed 45 figures are attached to the corresponding slabs slightly offset from the center. This offset arrangement of the brackets relative to the individual slab permits convenient assembly of a plurality of slabs in one row, since the brackets 50 on each slab are arranged so as not to interfere with the brackets of the adjacent slabs and also to provide for interchangeability of the individual slabs. The interchangeability of the slabs as previously shown, is limited, that is to say, the slabs 55 are interchangeable if held in a certain position in one plane. This arrangement as previously discussed in detail may suffice for ordinary purposes. However, if it is desired to make the slabs interchangeable in any position, in one plane, the 60 arrangement may be adopted which is shown in Figure 11. The brackets such as 87 and 88 are fastened to the corresponding slab 85 on an angle. It will be understood, of course, that the brackets on the other slabs are fastened to the corresponding 65 slabs in the same manner. This is shown in the case of the adjacent slab 86 which is partly broken away and illustrates the attachment of the two brackets 89 and 90, which are attached in the same manner to the slab 86 as the brackets 87 70 and 88 are attached to slab 85. When the brackets are attached in the manner discussed above, the slabs will be interchangeable in any position in one plane. This absolute interchangeability will prevent loss of time in attaching the 75 slabs to the wall or ceiling structure.

It will be recalled that one of the objects of my invention is concerned with a construction using cover slabs which are attached to an underlying structure by means of moulding. The cover slab shown in Figure 12 and designated by the 80 numeral 91 is for this purpose provided with two brackets 92 and 93. Each of these brackets 92 and 93 is provided with an angularly extending tongue such as 94 and 95, respectively, for attachment to the cover slab 91 by means of nails such as 96 and 97, respectively. These tongues are attached on the cover slab 91 in countersunk portions thereof, as shown. This countersunk attachment is provided in order to achieve a close attachment of adjacent slabs. Each of the brackets 90 92 and 93 is also provided with extensions such as 98-99 and 100-101, respectively, which project transversely from the cover plate 91. The end of each of these projections is formed into prongs. Thus, the projection 98 has prongs 95 102-103, and the projection 99 has prongs 104-105. The projections 100 and 101 of the bracket 93 are provided with similar laterally extending prongs.

Now, when it is desired to construct a wall or a 100 ceiling of cover plates such as the one shown in Figure 12, a platform will be provided for supporting the slabs such as 91 in predetermined positions in a certain plane. Concrete is then poured in back of the slabs which are arranged 105 on the platform, and the concrete will fill the intervening space between the underlying structure and the back of the cover plate, thereby embedding the projections and the prongs of the bracket attached to the cover plates. After the 110 concrete mixture or other suitable binding material which is employed, is dry, the platform may be removed.

It will be seen from the foregoing discussion that the invention disclosed in this case presents a 115 variety of distinguishing features. It presents, in the first place, a novel construction of a ceiling which may be extended to constructions of walls as well. Although I have shown the covering slabs to be made of wood fibres and having the function 120 of correcting the acoustics of a room, the invention is not limited to the use of any specific type of covering material as, obviously, any type of covering material regardless of its function may be employed. In the present case the function 125 of the covering slab is decorative as well as sound correcting. In this connection, the invention is of particular value since it increases the effect of the sound dissipating and sound correcting qualities of the covering slabs. The intervening 130 space between the covering slabs and the underlying structure, as provided for in certain embodiments of the invention, serves as a sound insulating chamber. The use of a special material such as felt for supporting the sound correcting slabs so that they retain their full effect is superfluous. The slabs may be mounted very rapidly and accurately in place, furnishing a neat work with the least expenditure of time and cost. Any desired design or pattern may be accomplished by using my invention.

It will be understood that several modifications of the invention are possible and will suggest themselves to those experienced in the art. It is therefore not my intention to limit myself in the 145 application of the invention precisely to the structure shown and described in the foregoing specification. What I consider new and distinguishing over the art is pointed out in the following claims.

- I claim as my invention:
1. In a sound correcting ceiling structure, a structural supporting framework comprising a plurality of supporting members, sound correcting cover plates for attachment to said framework in rows extending transversely thereto, spaced metallic brackets disposed in the plane of said cover plates adjacent said supporting members secured to said plates and projecting from one side thereof for interlocking engagement with preceding plates in a row to suspend said plates from said preceding plates, said brackets projecting from the other side thereof for direct attachment to said framework. 80
  - 15 2. In the construction of a ceiling having a framework comprising a plurality of supporting members disposed in parallel relation to each other, covering plates for exterior attachment to said members, and spaced interchangeable metallic brackets extending beyond opposite sides of and secured to said plates for supporting one side thereof in slidably interlocking relation by adjacent plates and for directly fastening the other side thereof to said supporting members. 85
  - 20 25 3. A plate of decorative and sound correcting material for exterior attachment to a structure provided with a framework for supporting a plurality of plates, a metallic mounting bracket for said plate, means carried by said bracket for attachment thereof to the bottom of said plate, and tongues on said bracket extending in the plane of the bottom of said plate and projecting therefrom on opposite sides thereof for fastening said plate to said framework. 90
  - 30 35 4. In a wall construction, a plurality of parallel supporting members, a plurality of rows of cover slabs and parallel brackets secured to the bottom of said slabs at unequal distances from the ends thereof and projecting beyond the sides 95 of said slabs, cooperating with said supporting members for attaching said slabs thereto to provide a covering for said wall, adjacent slabs in a row being reversed through an angle of 180 degrees in the plane of said slabs. 100
  - 40 5. Covering material for exterior attachment to a structure comprising a slab of predetermined size and shape, a mounting bracket for said slab, means on said bracket engaging the sides of said slab for attachment thereof to the bottom of said slab, said bracket projecting beyond the sides of said slab in the bottom plane thereof for mounting said slab. 105
  - 45 6. A plate of decorative and sound correcting material for exterior attachment to a structure provided with a framework for supporting a plurality of plates, a mounting bracket for said plate, means on said bracket engaging the sides of said plate for attachment thereof to the bottom of said plate, and tongues on said bracket extending in the bottom plane of said plate and projecting therefrom on opposite sides thereof for fastening said plate to said framework. 110
  - 50 7. A building unit comprising a substantially rectangular cover slab, a plurality of attaching brackets secured to the bottom and extending beyond the opposite sides of said slab, said brackets being arranged in spaced substantially parallel relation and at an angle to the center line of said slab extending in the general direction of said brackets. 115
  - 55 8. Covering material for exterior attachment comprising a plate of sound correcting material, spaced metallic mounting brackets disposed upon a face of said plate, attaching tongues struck from said brackets adapted to secure said brackets to said plates, said brackets extending beyond opposite sides of said plates for the purpose set forth. 120
